WALL AND PARTITION

Filed April 28, 1922

FIG. 1

FIG. 5

FIG. 4

FIG. 3

FIG. 2

INVENTOR:

Eric E. Hall

By John Howard Mullay
HIS ATTY.

UNITED STATES PATENT OFFICE.

ERIC E. HALL, OF CHICAGO, ILLINOIS.

WALL AND PARTITION.

Application filed April 28, 1922. Serial No. 557,100.

To all whom it may concern:

Be it known that I, ERIC E. HALL, a citizen of the United States, and a resident of Chicago, in the county of Cook and State 5 of Illinois, have invented certain new and useful Improvements in Walls and Partitions, of which the following is a full, clear, and exact specification.

My invention is concerned with certain 10 new and useful improvements in walls and partitions, and in a novel securing member adapted to be inserted therein, to which the furring strips are nailed.

To illustrate my invention, I annex here- 15 to a sheet of drawings, in which the same reference characters are used to designate identical parts in all the figures, of which,—

Fig. 1 is a perspective view of a portion of a wall embodying my invention;

20 Fig. 2 is a side elevation of two of the blocks overlapped;

Fig. 3 is an end elevation of one of the same;

25 Fig. 4 is a horizontal section on the line 4—4 of Fig. 2; and

Fig. 5 is a view similar to Fig. 4, but showing a modified construction.

In illustrating my invention, I have shown a floor *a* upon which is erected a partition wall made of a plurality of tile blocks *b*, or some other similar material adapted to be connected at the joints by the mortar *c*. For securing, for instance, the furring strips *d* in place to which the baseboard *e* 30 is in turn secured by the nails *f*, I employ the nailing blocks *g*, each of which preferably consists of a rectangular wooden strip *h* of suitable length enclosed by a sheathing of thin sheet metal, the outer face *j* of which 35 is preferably perforated, preferably by having the metal expanded, so that the nails *k* driven through the furring strips *d* may be more easily driven therein, although it will be understood that I might use a very thin 40 sheathing and drive the nails in by puncturing the outer face thereof. The sheathing is preferably formed of sheet-metal strips which have the tongues *l* suitably located on 45 one edge thereof so as to enter co-operating recesses *m* toward the other edge, so as to 50 secure the sheathing in place on the strip *h*, which might also be composed of some fibrous material secured together with a suitable binder. To anchor these strips in 55 place, I preferably employ the extended edge *n*, which is preferably perforated so as

to allow the mortar to pass therethrough by expanding that portion of the strip.

In building a wall, it will be understood that the strips *g* are put in place in such 60 of the vertical joints as may be desirable, the ends of the tile abutting the sides of the sheathing while the mortar *c* falls in the central portion between the opposed strips or blocks and penetrates the apertures in 65 the anchor portion *n*. When the furring strips *b* are thus nailed in place, the plaster surface *o* is applied in the customary manner, after which the baseboards *e* may be secured as shown, and upon this the hoods 70 *p* and the corner strips *q* may be nailed, if desired.

In Fig. 5 I have shown an alternative construction, in which the anchor strips *n'* are corrugated, as well as perforated, so that 75 the corrugations of one strip nest in the corrugations of the other strip, and it will be obvious that if the strips are needed for a thicker wall than the one shown, all that is necessary is to shift them so as to bring the 80 corrugations of one strip into co-operation with different corrugations on the other one.

While I have shown and described my invention as embodied in the form which I at present consider best adapted to carry out 85 its purposes, it will be understood that it is capable of modifications, and that I do not desire to be limited in the interpretation of the following claims except as may be necessitated by the state of prior art. 90

What I claim as new, and desire to secure by Letters Patent of the United States, is:

1. In a wall, the combination with a plurality of members adapted to be joined at their ends by mortar, of nailing blocks 95 adapted to be located in certain joints in place of some of the mortar, anchors secured to the nailing blocks and extending inwardly therefrom, mortar between the ends of the blocks and co-operating with the anchors to 100 prevent any possible outward movement of the blocks, and wooden strips nailed to the blocks.

2. In a wall, the combination with a plurality of members adapted to be joined by 105 mortar, of nailing blocks adapted to be located in pairs back to back on opposite sides of the wall in certain joints in place of some of the mortar, and wooden strips nailed to the blocks, said nailing blocks having overlapping anchors projecting inwardly therefrom to engage the mortar. 110

3. In a wall, the combination with a plurality of members adapted to be joined by mortar, of nailing blocks adapted to be located in pairs back to back on opposite sides of the wall in certain joints in place of some of the mortar, and wooden strips nailed to the blocks, said nailing blocks having overlapping and interlocking anchors projecting inwardly therefrom to engage the 10 mortar.

4. In a wall, the combination with a plurality of members adapted to be joined by mortar, of nailing blocks adapted to be located in pairs back to back on opposite sides of the wall in certain joints in place of some of the mortar, and wooden strips nailed to the blocks, said nailing blocks having overlapping and interlocking anchors projecting inwardly therefrom to engage the mortar, 15 the interlocking portions of the anchors being symmetrically arranged so that by varying the extent of the overlapping they can be adapted to walls of different thicknesses.

5. In a wall, the combination with a plurality of members adapted to be joined by mortar, of nailing blocks adapted to be located in pairs back to back on opposite sides of the wall in certain joints in place of some of the mortar, and wooden strips nailed to the blocks, said nailing blocks having overlapping and interlocking anchors projecting inwardly therefrom to engage the mortar, the interlocking portions of the anchors being longitudinally corrugated so that by 30 varying the corrugations brought into register they can be adapted to walls of different thicknesses.

6. As a new and useful article of manufacture, a nailing block composed of a fibrous

bar surrounded on all its sides by a connected 40 thin metal sheathing and provided on one side with anchoring means extending from the central portion of said side a substantial distance so that it can co-operate with the anchoring means of another nailing block 45 opposed thereto.

7. As a new and useful article of manufacture, a nailing block composed of a fibrous bar surrounded on all its sides by a connected 50 thin metal sheathing and provided on one side with anchoring means consisting of a perforated extension of the sheathing.

8. As a new and useful article of manufacture, a nailing block composed of a fibrous 55 bar surrounded by a thin metal sheathing and provided on one side with anchoring means consisting of a corrugated extension of the sheathing.

9. As a new and useful article of manufacture, a nailing block composed of a fibrous 60 bar surrounded by a thin metal sheathing and provided on one side with anchoring means consisting of a perforated and corrugated extension of the sheathing.

10. As a new and useful article of manufacture, a nailing block composed of a fibrous bar surrounded on all its sides by a connected 65 thin metal sheathing perforated on its outer face and provided on one side with anchoring means extending from the central 70 portion of said side a substantial distance so that it can co-operate with the anchoring means of another nailing block opposed thereto.

In witness whereof, I have hereunto set 75 my hand and affixed my seal this 19th day of April, A. D. 1922.

ERIC E. HALL. [L.S.]
